UNITED STATES PATENT OFFICE.

WILLIAM J. B. HARRIS, OF BONHAM, TEXAS.

SAFE-LOCK.

1,337,554.

Specification of Letters Patent. Patented Apr. 20, 1920.

Application filed June 13, 1918. Serial No. 239,853.

To all whom it may concern:

Be it known that I, WILLIAM J. B. HARRIS, a citizen of the United States, residing at Bonham, Fannin county, and State of Texas, have invented and discovered certain new and useful Improvements in Safe-Locks, of which the following is a specification.

My said invention relates to safes and more particularly to the locking means for the doors thereof and has for its purpose to provide a means which will necessitate the operation of a series of setting devices before the several bolts can be moved to unlock the door.

Another object of the invention is to place certain of the setting devices on the door and others on the safe where they would not ordinarily be seen by any one unfamiliar with its operation.

Referring to the accompanying drawings which are made a part hereof and on which similar reference characters designate similar parts in the different views shown:

Figure 1 is a perspective view of a safe having a locking means constructed in accordance with my invention,

Fig. 2, a vertical section on the line 2x2 of Fig. 1 showing the door locked,

Fig. 3, a detail section on the line 3x3 of Fig. 2, and

Fig. 4, a detail perspective of the rotatable safety block.

In the drawings, the numeral 10 represents the body of the safe which is mounted on the usual rollers 11, and 12 designates the door which is mounted to swing on the usual hinges 13 and which carries a series of pairs of locking bolts. These bolts designated by 14 and 15 are arranged for vertical movement, while all other bolts 16 are arranged for horizontal movement. The bolts 14 are connected to the bolts 15 by means of bars 17 and 18 as shown in Fig. 2. Each one of the pairs of bolts 16 is pivoted as at 19 to a connecting rod 20 which is in turn pivotally connected as at 21 to the end of a two armed lever 22 mounted for oscillation on a pin 23 secured to the door 12. The arm 24 of each of the levers 22 is slotted as at 25 to receive a pin 26 carried by the adjacent bar 17 or 18.

Pivoted at 27 to the door 12 is a lever 28 provided with two slots 29 in which operate pins 30 independently secured to the bars 17 and 18. On one end of the lever 28 is

formed a toothed segment 31 which is in mesh with a pinion 32 secured on the stub shaft 33 which is operated by the knob 34. (See Fig. 1). Opposite to the segment 31, the lever 28 is provided with a flat end 35 which is adapted to bear against a safety block 36 when the door is locked. This safety block 36 consists of a cylindrical member rotatably mounted on a stub shaft journaled in the bearings 37 that are secured to the doors as shown. A circumferential groove 38 is formed in the block midway of its ends and transversely intersecting said groove 38 is a vertical and arcuate groove 39 extending from the upper edge to the lower edge of the block and is in mesh with a similar pinion 41 secured to a shaft 42 which is provided with an operating knob 43.

It will be readily seen from the foregoing that when the safety block 36 is rotated by means of the knob 43 to bring the groove 39 into register with the end 35 of the lever 28, the said lever 28 is free to be rocked on its pivot 27 by means of the knob 34 and its accompanying gear and rack, which will cause the rod 17 to be moved up and the rod 18 to be moved down thereby rocking the levers 22 and imparting a corresponding movement to the several bolts 14, 15 and 16.

The lever 28 is thus rocked until its end 35 registers with the groove 38 in the safety block and said block is then given a slight turn in either direction to confine the end 35 therein. When in this position the several bolts are entirely withdrawn from the openings in the casing 10 rendering this portion of the securing device unlocked. However should anyone, unfamiliar with the elements of the lock, turn the knob and lower the end 35 of the lever 28 to that portion of the groove 38 which lies below the groove 39, the device would remain locked owing to the protruding of the bolts which are normally seated within the door proper, as shown clearly in Fig. 2.

As a further means of securing the door in locked position, there is slidably mounted a bolt 44 in brackets 45 on the door 12. This bolt 44 passes through an opening 46 in the side of the door and is adapted to enter an opening 47 in the body of the safe. The sliding motion is imparted to the bolt by means of a pinion 48 which meshes with a rack 49 formed on said bolt. The pinion 48

48 is mounted on the end of a shaft 50 which projects through the front of the door 12 and is provided with an operating knob 51. A disk 52 is mounted within an opening in the bolt 44 and said disk has a flat portion 54 for a purpose to be explained. Said disk 52 is secured to one end of a shaft 55 that projects through the front of the door 12 and has mounted thereon an operating knob 10 56 (see Fig. 1) and is arranged so as to bring its curved edge portion 53 into either of the depressions 57 or 58 formed in the bolt, thereby securing the same when it is in either locked or unlocked position. When 15 it is desired to move the bolt, the disk 52 is rotated to bring the flat portion 54 adjacent the depressions 57 and 58 thereby releasing the bolt for movement.

Additional means to that just described 20 are provided for securing the bolt 44 when in locked position and said means consists of a pair of pivoted hooks 59 and 60 which engage within notches 61 and 62 formed in the upper and lower surfaces of the bolt 44 25 at the end thereof. Both hooks are spring pressed to normally hold them in engagement with the notches and are also flexibly connected with operating rods 63 and 64 which are provided with knobs or handles 30 65 and 66 respectively. The rods 63 and 64 are provided with upstanding lugs 67 and 68 respectively which are adapted to pass through notches 69 and 70 formed in a pair of locking disks 71 and 72 35 when the notches are turned to be in line with the path of movement of the lugs. The disks 71 and 72 are secured to stub shafts 73 and 74 which pass through the side casing of the safe and are provided 40 with operating handles 75 and 76 respectively. A ratchet wheel on each of the shafts 73 and 74 is acted upon by a spring pawl for holding the shaft and its disk in different positions. In the operation of this 45 last mentioned portion of the device, in order to unlock the bolt 44, it is necessary to just align the notches 69 and 70 with their respective lugs 67 and 68 and then push on the knob 65 and pull on the knob 66.

50 It is to be understood that those skilled in the art to which this invention pertains may change the proportions and minor details without departing from the spirit of the invention; also, that the portions designated 43, 56, 75 and 76 in the drawings may be made in the form of any suitable "combination lock" instead of the simple structure shown in the drawings.

Having thus fully described my said in-

vention, what I claim as new and desire to 60 secure by Letters Patent, is:

1. The combination with a door having groups of adjacent perforations in several edges, a frame having sockets registering with the perforations of the door, a pair of 65 bolts for each group having their extremities inserted through the perforations and normally substantially flush with the edge of the door, and connected means adapted to slide the bolts of each pair longitudinally 70 one into one of the sockets and the other within the door structure.

2. The combination with a door having a plurality of pairs of perforations in one edge, of a frame having sockets registering 75 with the perforations, a pair of bolts for each pair of perforations having their extremities inserted through such perforations and normally substantially flush with the edge of the door, and a plurality of connected 80 walking beams within the door structure between and adapted to slide the bolts one of the bolts of each pair into one of the sockets and the other within the door structure.

3. The combination with a door having adjacent perforations in its opposite edges, of a frame having sockets registering with the perforations, bars extending entirely across the door in general parallelism with 90 bolts carried upon the extremities of the bars and slidable within the sockets, and a walking beam within the door structure adapted to slide the bars simultaneously and in opposite directions, one of the bolts of 95 each bar entering one of the sockets, the other sliding within the door structure.

4. The combination with a door having adjacent perforations in its opposite edges of bars extending entirely across the door 100 in general parallelism, one of said bars being provided with spaced reentrant angles, a walking beam pivoted between the bars and adapted to move the bars simultaneously in opposite directions, a segment carried by the walking beam having extremities adapted to lockingly engage within one of the reentrant angles determined by the longitudinal position of the bar and bolts carried by said bars.

In witness whereof I have hereunto set my hand and seal at Bonham, Texas, this 8th day of June, A. D. nineteen hundred and eighteen.

WILLIAM J. B. HARRIS. [L.S.]
Witnesses:

C. A. WHEELER,
EULA MULLINS.
